UNITED STATES PATENT OFFICE.

NOAH F. CRABILL, OF BRUNSWICK, MARYLAND.

RAILWAY TIE.

Application filed December 23, 1927. Serial No. 242,076.

This invention relates to improvements in railway ties and more particularly to ties of composite molded structure.

It has been heretofore proposed to employ, 5 as a substitute for wood ties, ties molded from concrete or cement, and such ties have been provided with various types of securing means for holding the rails in position thereon, but as a rule, ties of this construction 10 have proved to be unsatisfactory inasmuch as the rail securing means has ordinarily been embedded directly in the ties and either pulled loose, in time, or the vibration to which such devices and the ties are subjected, 15 through the vibration of the rails in the passage of rolling stock thereover, results in a cracking or disintegration of the tie body and a loosening of the securing means, or the tie body is rendered incapable of properly supporting the rails. Therefore the present invention has as its primary object to provide 20 a composite tie comprising a body of cement or other similar material, capable of being molded to the required form, and novel means 25 whereby the rails, disposed upon the tie, may be anchored thereto without any liability of the anchoring means becoming loosened or disarranged or in any way becoming ineffective for the purpose intended.

The tie embodying the invention consists, 30 generally speaking, of a tie body which is of cement or other similar material capable of being molded to the desired shape, and blocks of wood which are housed within recesses in 35 the body and into which the rail securing spikes may be driven, substantially in the same manner as in the case of the ordinary wood ties, and in this connection the invention has as a further object to provide a novel 40 arrangement of said blocks providing for a firm anchorage of the spikes and consequently firm anchorage of the rails to the tie, the invention further contemplating an arrangement such as to permit of the ejection or driving out of the blocks, in the event they become 45 decayed after long exposure to moisture and the elements, and new blocks, at the same time, driven into place in the recesses in the tie, so that the life of the tie body itself may be 50 greatly prolonged, thus effecting an economy in the use of the ties.

Another object of the invention is to provide a tie of the class described so constructed that car replacers may be readily anchored thereon when the use of such devices is necessary, because of derailments. 55

Another object of the invention is to provide a tie of the class referred to so constructed that it may be conveniently handled by the ordinary tongs employed in handling 60 wood ties.

While the accompanying drawings and the description which is to follow, constitute a disclosure of the preferred embodiment of the invention, it will be understood that various 65 changes may be made within the scope of what is claimed.

In the accompanying drawings:

Figure 1 is a view in elevation of a railway tie constructed in accordance with the present invention, the view illustrating rails mounted upon the tie and spikes securing the rails in place; 70

Figure 2 is a top plan view of the tie, the rails which are disposed thereon being shown 75 in broken lines and the spikes being similarly shown;

Figure 3 is a detail vertical longitudinal section view through one end of the tie;

Figure 4 is a vertical transverse sectional view taken substantially on the line 4—4 of Figure 1 looking in the direction indicated by the arrows. 80

The tie embodying the invention comprises a body 1 which may be of any suitable composition of cement and sand, as for example forty per cent cement, forty per cent sand and twenty per cent stone, in pieces of approximately one-half inch in size, and, in the carrying out of the invention, the body is 85 molded so as to provide a pair of vertical rectangular recesses 2 near each end of the body, these recesses being of uniform dimensions from their upper to their lower ends and extending entirely vertically through the body. 90 For a purpose to be presently explained the body is also formed, at the time of molding, with a pair of recesses 3 located at opposite sides of each pair of recesses 2, the recesses 3 being preferably equi-distantly spaced from the respective recesses 2 as clearly shown in 95 Figure 2 of the drawings. After the body 100

of the tie has been molded, substantially cubical blocks 4 of wood are driven into the recesses 2, and these blocks are preferably of such dimensions that they will fit with sufficient snugness in the respective recesses as to necessitate the application of force in driving the same into the recesses, thus insuring of a permanent retention of the blocks within the respective recesses through the frictional contact of their faces with the walls of the recesses. Likewise the blocks are of a height equal to the thickness of the tie body, so that the top and bottom faces of the blocks are flush with the upper and under sides of the tie body.

It will now be evident by reference to Figures 1 and 2 of the drawings that the blocks 4 at each end of the tie body are so spaced that rails disposed upon the tie body will each 20 rest at its base flanges upon the upper ends of blocks, the blocks being so arranged that the outer margins of the base flanges of each rail will be spaced inwardly from the relatively remote sides of the upper faces of the blocks 25 with which they are disposed in contact, so that spikes, indicated by the reference letter S, may be driven into the blocks to secure the rail in place. It will likewise be evident at this point that, due to the provision of the 30 wood blocks 4 which are anchored by friction in the recesses 2 in the tie body, ordinary spikes may be employed in securing the rails upon the ties embodying the invention, as distinguished from the employment of specially 35 constructed securing means which has heretofore been found necessary where an attempt has been made to employ concrete or cement ties. It will likewise be evident that when the 40 spikes are driven into the blocks, the wood of the blocks will be to some extent expanded, so that an even firmer contact of the faces of the blocks with the walls of the recesses in which they are seated, will be provided for, thus 45 positively insuring against any accidental displacement of the blocks.

With reference to the recesses 3 which are formed in the tie body at each side of each pair of recesses 2, these recesses are designed to accommodate wood blocks 5 which do not differ from the blocks 4 except that they are of 50 oblong rectangular form and are disposed longitudinally medially with respect to the tie body 1, the upper and lower ends of these blocks being flush with the upper and under 55 sides of the tie body and the blocks constituting penetrable supports upon which the spurred base of a car replacer may be arranged when the use of such device becomes necessary. Therefore, notwithstanding the 60 fact that the tie bodies are of cement or concrete, or other plastic and molded material, car replacers may be used with the same degree of facility as at present, where they are employed upon tracks embodying wood ties.

In order that the body of the tie may be reinforced, heavy wire mesh sheets are preferably embedded in the body at the time of molding and are preferably arranged in spaced relation one above another in the ends of the body and in the portions of the body intermediate relatively adjacent ones of the recesses 2 and 3, as clearly shown in Figures 3 and 4 of the drawings.

In order that the tie body, embodying the invention, may be conveniently handled by the use of tongs as in the handling of wood ties, sockets 7 are formed in the opposite longitudinal faces of the tie body at suitable intervals and these sockets are designed to accommodate the pointed jaws of the tongs when the tongs are applied to the tie.

It will be evident that, in the event the blocks 4 or the blocks 5 become partly or wholly decayed due to a long period of exposure to the elements and to moisture in the road bed, these blocks may be readily replaced by disposing other new blocks directly upon the tops thereof and then forcing the new blocks into place in the recesses, thus, at the same time, effecting an ejection of the old blocks from the recesses.

Having thus described the invention, what I claim is:

1. A railway tie comprising a plastic body having a pair of rectangular recesses formed vertically therein and opening through its upper and under sides, each recess having its walls perpendicular to the planes of the upper and under sides of the tie and each recess being of uniform dimensions from end to end, and blocks of wood frictionally retained within said recesses and having faces presented at the upper side of the body, the recesses and blocks being so arranged as to provide for exposure of portions of the faces of the blocks beyond the margins of the base flanges of a rail disposed upon the body, whereby securing spikes may be driven into said blocks through the exposed portions of the upper faces thereof to secure the said base flanges of said rail.

2. A railway tie comprising a plastic body provided near each end with spaced vertically extending recesses opening through its upper and lower sides, the recesses being of rectangular contour and having their relatively adjacent walls spaced apart a distance less than the width of the base of a standard rail, the relatively remote walls of the recesses of each pair being spaced apart a distance greater than the width of the base of a standard rail, and a rectangular block of wood driven into each of said recesses and frictionally held therein and having its upper and lower ends flush with the upper and under sides of the said body, the blocks constituting means whereby spikes may be driven into the tie to engage the base flanges of rails

disposed upon said tie above the upper ends of the blocks.

3. A railway tie comprising a plastic body having means whereby a rail base may be secured thereon, the body being formed at opposite sides of said means and in spaced relation thereto with recesses extending vertical-

ly in the body and opening through the upper and under sides thereof, and blocks of wood seated frictionally in the said recesses and constituting means whereby a car replacer may be anchored to the tie body for use. 10

In testimony whereof I affix my signature.
NOAH F. CRABILL.
